BAG FILLING MACHINE

Original Filed Aug. 29, 1924

UNITED STATES PATENT OFFICE.

ROBERT P. BUSHMAN, OF SOUTH ORANGE, NEW JERSEY, ASSIGNOR, BY MESNE ASSIGNMENTS, TO BATES VALVE BAG CORPORATION, OF CHICAGO, ILLINOIS, A CORPORATION OF NEW JERSEY.

BAG-FILLING MACHINE.

Original application filed August 29, 1924, Serial No. 735,001, and in Germany June, 1927. Divided and this application filed September 2, 1927. Serial No. 217,089.

This invention relates to bag filling and weighing machines with special reference to types in which finely powdered or granular material such as cement, is deposited in definite quantities by weight, into bags having a relatively small lateral opening at their upper ends, commonly known as valve bags. The subject matter of this application is disclosed in a joint application of the inventor together with Edward L. Bushman and Nathan M. Fegely, filed August 29, 1924, Serial No. 735,001.

An object of the invention is to provide a pivoted delivery spout actuated automatically upon completion of the filling operation to positively close the inlet passage in a substantially frictionless manner. A manually operated auxiliary means for preventing flow until an empty bag has been submitted for that previously filled may be supplied.

The action of the automatic cut-off is dependent upon the operation of a compound weighing device comprised of a platform scale carried on a pair of parallel levers mounted one above the other on knife-edge pivots and capable of being accurately adjusted by counterpoises to the predetermined weight of material to be entered in each bag, thus tending to economy, speed, and convenience in handling.

The delivery spout is preferably flared to facilitate delivery and prevent possible clogging, and adjusting devices are supplied at all desirable points.

The invention consists in the novel features of construction, arrangement and combination of parts embodied, by way of example, in the apparatus hereinafter described as illustrating the preferred form of the invention, and the invention will be more particularly pointed out in the appended claims.

Further objects and advantages of the invention will more fully appear from the following description taken in connection with the accompanying drawings which

show, by way of example, the preferred embodiment of the invention.

Referring to the accompanying drawings, in which the same reference characters indicate the same parts in the various ways, Figure 1 is a partial front elevational view of one embodiment of the invention; Fig. 2 is a fragmentary longitudinal sectional view of one form of delivery spout and valve, taken on the center line and drawn to an enlarged scale; Fig. 3 is a top plan view of the part shown in Fig. 2; Fig. 4 is a view similar to Fig. 2, but showing the spout inclined and the valve closed.

Machines for the purpose outlined are usually composed of a series of units, disposed in parallel spaced relation upon a common base or foundation, supplied from a single feed trough and actuated by a power-driven shaft.

The preferred type of such machine as shown in the accompanying drawings, consists of side frames, generally denoted by the numeral 20, composed of bases 21 having forwardly extending elements and raised columns, convergently inclined at their upper ends.

Connecting between pairs of these frames, at their bases, are the members, as the rolled beams 22, held rigidly by riveted angles 23, and at the front by a cross beam 24 having flanged ends 25 also riveted to the frames.

The frames are further held in rigid relation at their upper converging ends by being secured to the bottom of a feed trough 26 into which the material is supplied in any convenient manner.

Material is fed from the feed trough 26 into hoppers 29, but one of which is shown in the drawings. The hopper 29 has converging side walls, and has mounted therein a shaft 30, driving an impeller, not shown, used to agitate and force the material forward to the outlet, to which is secured a hollow, elbow-like valve connection 32.

A bracket 33 is fixed on the upper horizontal face of the beam 22, the bracket having an upright extension 34. Bifurcated

bosses 35 on the brackets and similar bosses 36 on the extensions are formed with open topped, V-shaped seats or recesses to receive knife-edge elements 37 and 38 set respectively in levers 39 and 40, relatively lower and upper, at about the center of their lengths.

These levers extend centrally between the frame sides, from near their rear columns to points substantially in a vertical plane with 10 the bar 24, and are connected in parallel by a pivoted yoke 41 at their rear ends.

The lower lever has mounted thereon a weight of considerable magnitude, and the upper lever has mounted thereon a lesser 15 weight, these weights being mounted and adjusted in a suitable manner, not shown.

The front ends of the levers are united by a link 46, the connection comprising knife-edge pivots 49 and 50. Link or bar 46 is constrained to move in a vertical plane due to 20 the parallel link action of the ends of the levers connected thereto.

A pad 51 at the bottom of bar 46 contacts with a seat 52 carried on a support 53 integral with the cross beam 24, forming a solid 25 abutment to receive the impact of the bar 46 upon its descent.

Carried at the upper end of the bar 46 is a ribbed plate 54 on which rests the base 55 30 of a scale having a platform 56 to which is attached a rearwardly reaching arm 57 carrying the stem 58 of a forked yoke 59 pivotally supporting a curved apron or guide plate 60 adapted to position a bag, not shown, centrally on the platform 56 and partially supporting the bag as it becomes filled.

The upright 62 of the platform scale frame is secured to lugs 63 of the base 55 and its horizontal arm 64 is provided with a graduated scale beam 65 and adjustable weight 66 40 by which the load on the platform 54 may be accurately determined.

The outer flange of valve connection 32 is disposed in a perpendicular plane, facing the 45 front of the machine, and attached to it is a rectangular valve body 70 having a smoothly finished concave face 71, the axis of which is in a horizontal plane.

Rigidly fixed on opposite sides of the valve 50 body 70 or discharge throat are forwardly extending arms 72 and 73 having inreaching hubs at their ends, the arm 72 carrying a set-screw 75 and the opposite arm having journaled in it a spindle 76.

The point of the set-screw 75 and inner end 55 of the spindle bear upon bosses 77 fixed on opposite sides of a spout 78, at its cylindrical end adjacent the discharge throat 70, the outer portion of the spout being preferably 60 flared or expanded at its outer side 79, and cut angularly, as at 80, from a point in the flared portion to the opposite upper side, presenting a thin narrow entering end 81 suited to readily enter an opening in the

upper edge of the bag, the shape of the discharge opening being ovoidal and of greater area than the inlet opening of the spout. Spout 78 when so entered in the opening of a bag serves to support the bag by the top thereof; a part of the load being also carried, when 70 the bag is filled, by a platform 56.

Spout 78 is swung upon the axis of the spindle 76, by means of an arm 82 fixed to the spindle and pivotally engaged at its outer end by a rod 83, connected by a turnbuckle 75 84 with the rod 85 pivoted to a bracket 86 fixed on the side of the platform 56, opposite the scale upright 62.

From the foregoing it will be seen that when the platform 54 is in a raised position, 80 spout 78 will be held substantially horizontal, but when the platform is lowered, the spout will be swung upon its pivots into the position indicated in Fig. 4.

It is, therefore, obvious that, since the top 85 of spout 78 is in supporting engagement with the upper lip of the bag, as the spout is moved to a downwardly inclined position shown in Fig. 4, the downward force of the filled bag will cause the bag to slide forward and downwardly along spout 79.

A flat bar 87 is disposed horizontally across the center of the opening in the valve body 70, the front face of the bar containing a concave recess 88 presenting sharply defined lateral wiping edges, and similar recesses 89 are formed in the concave face of the valve body above and below the bar 87. 95

Fixed on the end of spout 78 is a band or heavy ring 90 formed on a convex head 100 91, suited to closely engage and particularly rotate against the concave face 71 of the discharge throat on the axle 76.

This head 91 has a transverse bar 92 across its center, corresponding to the bar 87 of the discharge throat, and like it, being concavely recessed as at 93, other recesses 94 being formed in the head in parallel planes.

Thus when the spout 78 is extended horizontally, as best shown in Fig. 2, openings 95 in the discharge throat will register with the similar openings 96 in the head 91, permitting powdered or granular material to flow freely from the hopper 29 through the valve and out at the end of the spout 78, provided material is present in the hopper and is being propelled therefrom. 110 115

Contriwise, when spout 78 is inclined downwardly, as shown in Fig. 4, due to the weight of material entered into the bag, tilting the scale levers 39 and 40, passages 95 in the discharge throat are closed by the valve head and no material can flow outward. 120

The purpose of the recesses in the valve body and in the similar recesses in the head is to reduce friction, thereby rendering the device highly sensitive and for the purpose of presenting relatively sharp scraping edges at 125

opposed surfaces tending to remove any accumulations and prevent clogging during their relative movement, in a manner that will be readily understood.

5 In operation, an empty bag is placed on platform 56 adjacent apron 60, and spout 78 inserted in a small side opening in the bag which is partially sustained by the spout.

Upon opening a suitable valve and allowing material to flow into hopper 29 and being propelled therefrom, the material passes through the spout into the bag until the weights on the scale beams are overcome and plate 54 is lowered and the spout is inclined, 15 shutting off further flow and simultaneously allowing the filled bag to slide downwardly and off the spout. A suitable valve may then be closed, a filled bag removed from platform 56, and another empty bag substituted, the 20 spout and platform rising immediately upon the removal of the filled bag, the weight of which can be ascertained and checked by reading the scale beam.

In addition to acting as a cut-off, the pivoting of the spout facilitates the discharge of the filled bag. It will be clear that, when the spout is pivoted, the bag may be slid therefrom by moving its top without removing the bottom of the bag from the supporting platform. If the filling spout were held rigidly in a horizontal position, it would be difficult to remove the bag therefrom without removing it also from the bottom support. Furthermore, the pivoting of the spout, especially in the substantially frictionless manner shown, allows the operation of the scale beams practically without interference by the spout.

It will be obvious that various changes may be made in the construction shown within the terms of the appended claims which devise my invention.

What I claim is:

1. In a valve bag filling machine, the combination of a rigid discharge throat, a pivoted bag supporting and filling member for holding the opening of a bag to be filled in position to receive material from said throat, and means to tilt said support downwardly, to thereby allow said filled bag to move downwardly thereon.

2. In a valve bag filling machine, the combination with a rigid discharge throat, of weighing means, a pivoted bag supporting member for holding the valved opening of a bag to be filled in position to receive material from said throat, and means to tilt said support downwardly responsive to said weighing means when said bag has been filled, to thereby cause said filled bag to move downwardly along said support.

3. In a valve bag filling machine, the combination with a rigid discharge throat having an opening, of a pivoted filling spout hav-

ing an opening in register with said throat 65 opening and extending therefrom in the direction of said throat opening, and a member positioned to support the bottom of a valve bag having its valve threaded on to said spout.

4. In a valve bag filling machine, a rigid 70 discharge throat, a pivoted spout engaged therewith, and means movable relatively to said discharge throat for supporting a bag in cooperative relation with said pivoted spout.

5. In a valve bag filling machine, the combination with a rigid discharge throat having 75 an outlet passage therein, of a pivoted filling spout extending therefrom in the direction of said passage, and adapted to enter the valve of a bag, a member beneath said spout for supporting the bottom of a bag on said spout, and cooperative means formed on said throat and spout for closing the passage through said throat when the bag is discharged from said member.

6. In a valve bag filling machine, the combination with a rigid discharge throat having an outlet passage therein, of a pivoted filling spout extending therefrom in the direction of said passage, and cooperative means 90 formed on said throat and spout becoming operative upon inclining the spout on its pivots for closing the passage through said throat.

7. A valve bag filling machine comprising 95 a hopper provided with a discharge throat having a concave recess disposed across its face, a spout pivoted to said throat at the axis of the recess, and horizontal partitions adjacently disposed in the openings in said 100 throat and said spout respectively, said partitions closing the passage through the openings when the spout is inclined upon its pivotal axis.

8. A valve bag filling machine comprising 105 a hopper provided with a discharge throat having a concave recess disposed across its face, a spout pivoted to said discharge throat at the axis of the recess, convexly recessed horizontal partitions adjacently disposed in the openings of said throat and said spout respectively, said partitions closing the passage through the openings when the spout is inclined upon its pivotal axis, and means in the proximate surfaces of said throat and 110 spout adapted to reduce to a minimum the areas in contact and produce sharply defined scraping edges.

9. In a valve bag filling machine, the combination with a rigid discharge throat, of a 115 pivoted filling spout cooperating therewith, and means in the proximate surfaces of said throat and spout adapted to reduce to a minimum the areas in contact and produce sharply defined scraping edges.

10. The combination in a valve bag filling machine having a rigid discharge throat and a spout movable relative thereto, of a cut-

off collar intermediate the throat and spout, and a support adapted to hold the bag in co-
said collar being fixed to one of said elements, operative relation with said spout.
the opposite face of said collar presenting sharply defined edges to the other of said
elements.

11. In a valve bag filling machine, means providing a discharge passage, and a pivoted filling spout adapted to enter the valve of a bag for receiving material from said passage

12. In a valve bag filling machine, a rigid discharge throat and a pivoted spout engaged therewith, said spout having a constantly increasing cross-sectional area.

15 In testimony whereof, I have hereunto signed my name to this specification.

ROBERT P. BUSHMAN.
